UNITED STATES PATENT OFFICE.

CHRISTIAN P. PAULSEN, OF SEATTLE, WASHINGTON.

THREE-IN-ONE CLAMP AND VISE COMBINED.

1,425,275.

Specification of Letters Patent. Patented Aug. 8, 1922.

Application filed May 12, 1921. Serial No. 463,890.

To all whom it may concern:

Be it known that I, CHRISTIAN P. PAULSEN, a citizen of the United States, resident of Seattle, in the county of King and State 5 of Washington, have made a certain new and useful Invention in Three-in-One Clamps and Vises Combined; and I declare the following to be a full, clear, and exact description of the same, such as will enable 10 others skilled in the art to which it appertains to make and use the invention, reference being had to the accompanying drawings, and to letters or figures of reference marked thereon, which form a part of this 15 specification.

Figure 1 is a perspective view of the invention.

Figure 2 is an end view of the same.

Figure 3 is a detail perspective view of 20 the bench plate.

Figure 4 is a detail face view of the face plate.

Figure 5 is a detail plan view of the same.

Figure 6 is an end view of a modification showing the base of the device extended.

Figure 7 is a detail end view of the cross-head, the clamp member and the screw.

The invention has relation to clamping devices, and has for its object the provision of an implement of this nature capable of use as a clamp, a vise, or a pipe straightener, and adaptable to a variety of other uses. Other objects and advantages will herein- 35 after appear.

The invention consists in the novel construction and combinations of parts, as hereinafter set forth.

In the accompanying drawings, illustrating 40 the invention, the numerals 1—1 designate lateral frame bars, connected at each end by an arcuately formed member disposed at right-angles thereto, and which may be additionally connected at one end by a bar 45 8, lying in the plane of said frame bars. One of these arcuate members, 2, forms the stationary jaw of a clamp to be described, while the other member, 3, forms the bearing member of the clamp, and is provided with a 50 threaded perforation 4, engaged by a screw 6, carried by an arcuately formed movable jaw 7 of the clamp, said movable jaw slidably engaging the frame bars 1—1, and 55 adjustable toward and away from the fixed jaw.

The parts so far described form a strong

and serviceable clamp, useful in connection with a variety of work.

In order to adapt the device for use in clamping cylindrical articles, or as a pipe 60 or rod straightener, a clamp member is provided comprising a cross-head 9, adapted for sliding movement in longitudinal grooves 10—10 of the frame bars, and an arcuately formed clamp member 11, provided with 65 a screw 12, having threaded engagement with said cross-head, and working at right-angles to the screw 6.

In this use of the device, the pipe or rod is inserted between the arcuate faces of 70 the members 2 and 3 and the oppositely disposed arcuate face of the clamp member 11, the latter member being then operated by screw 12 to clamp or bend the article being operated upon. In use as a straightening 75 device, the clamp member 11 would be slid to position intermediate the opposed faces of the members 2 and 3; whereas if it is necessary to avoid bending of the work, the member 11 is positioned beneath the member 2. 80

When used as a vise it is necessary to secure the implement to a work bench, and for this purpose a plate 13 is provided, said plate having perforations 14—14, adapted for engagement by securing bolts. Plate 13 85 being inserted in the grooves 10—10 of the side bars, is slid home to the closed ends of said grooves, adjacent the bar 8, said plate being then bolted to the bench and drawn down tightly thereupon, the main clamp being now in position for use.

In order to hold small tools, as necessary in filing and sharpening the same, and for other similar work, a face plate 15 is provided, said plate being adapted to be bolted 95 to the movable jaw 3 of the clamp, and having channels 16 of various forms upon the clamping face thereof.

The fixed jaw member 2 may be formed with a flat upper face 17, useful as an anvil 100 in straightening nails and other small articles. The outer face 18 of this member may be provided with perforations 19 of varying diameter, useful as dies in punching holes in sheet metal.

The device is simple in construction, very strong and durable, and is capable of a wide variety of uses.

Guide rods 20, secured to the movable jaw 7, engage perforations 21 of the head 110 3 and serve to secure an even movement of the jaw.

Preferably the faces of the clamp jaws 2 and 7 are scored or roughened as shown at 22, and may be provided with transverse channels 23. Small pegs 24 may be inserted in the exterior faces of these jaws, being useful in holding annular articles and also in connection with an engraving block. The upper faces of the frame bars 1-1 may be graduated in accordance with any desired system of measurement.

In Figure 6 of the drawings the base of the device is shown as extended to form perforated lugs 25, for the accommodation of attachment bolts whereby the vise may be secured to a work bench.

I claim:

In a device of the character described,

lateral longitudinally grooved frame bars, an arcuate bearing member connecting said bars at one end, an arcuate jaw member connecting said bars at the opposite end, an arcuate jaw member having sliding engagement with said frame bars and provided with a screw engaging said bearing member, and a clamp member slidable in the grooves of said frame bars and provided with a screw disposed at right-angles to the screw of said sliding jaw member.

In testimony whereof I affix my signature, in presence of two witnesses.

CHRISTIAN P. PAULSEN.

Witnesses:

JAMES A. O'NEIL,
MICHAEL M. GIMSE.
